(57) **CLAIM**

The ornamental design for a power router tool, as shown and described.

DESCRIPTION

FIG. 1 is a front left side perspective view of the power router tool showing my new design;

FIG. 2 is a rear right side perspective of the tool shown in FIG. 1;

FIG. 3 is a left side view of the tool shown in FIG. 1;

FIG. 4 is a right side view of the tool shown in FIG. 1;

FIG. 5 is a top plan view of the tool shown in FIG. 1;

FIG. 6 is a front end view of the tool shown in FIG. 1; and,
FIG. 7 is a rear end view of the tool shown in FIG. 1.

The subject matter depicted in broken lines is not intended to be part of the claimed invention and is shown only for environment purposes.
